UNITED STATES PATENT OFFICE

2,534,305

METHOD AND APPARATUS FOR SEALING
CONTAINERS

John M. Sharf, Lancaster Township, Lancaster County, Pa., assignor to Armstrong Cork Company, Lancaster, Pa., a corporation of Pennsylvania

Application June 27, 1947, Serial No. 757,545

11 Claims. (Cl. 226—82)

1 This invention relates to a method and apparatus for sealing containers. The invention is particularly concerned with a method and apparatus for vacuum-sealing containers by the directional flow of steam or other hot vapor within the open mouth of a container above the container contents to displace the air therein and the positioning of a closure in sealed relationship with the container, the head space of which is filled with vapor, and thereafter permitting the vapor to condense, effecting a reduction in pressure within the container.

At the present time, food containers are frequently vacuum-sealed by passing the filled containers through a steam chamber in which is positioned a closure-applying mechanism. The steam envelops the entire container, and a substantial quantity of the air within the container is replaced by the steam prior to the application of the closure. Most commonly, the container is moved progressively through the steam chamber, and the closure is automatically applied in the chamber as the container moves therethrough.

In other sealing machines, the container is positioned within a cowling or other similar confining means, and steam is injected into the mouth of the container with a cap positioned above the container. The cap is then thrust down on the container, entrapping the steam therein.

The first-mentioned method of sealing is objectionable for a number of reasons, among which are the following: In moving a series of containers at high speed through a steam chamber, there is a tendency to create air drafts and also uncontrolled turbulence within the steam chamber, and, as a frequent consequence, the degree of pressure reduction within the sealed container is not as high as desired. The contaminated air which is not wholly replaced by steam also tends in some instances to deteriorate the packaged product. Another objection to this system is the fact that by merely enveloping the whole container in a steam atmosphere, it is difficult to quickly displace the air within the container above the container contents. This results in contamination of certain food products due to the incomplete scavenging of air from within the container. Since the steam must be diffused throughout the steam chamber in this system, there is always the danger of improper vacuumization resulting from the replacement of air within the head space in the container with a mixture of contaminated air and steam, resulting from the incomplete diffusion of steam

2 within the steam chamber and producing a poor quality of steam-air mixture.

In the second system, it is very difficult to inject steam at relatively high velocity into the open mouth of the container without at the same time entraining air with the jet of steam. Entrained air disposed within the container has the same deleterious action as air normally present in the container and not removed during the sealing operation.

It is an object of my invention to provide a method and apparatus for sealing containers in which the containers may be moved at a rapid rate and substantially complete scavenging of the air from the containers effected prior to the application of the closures.

A further object of my invention is to provide a method and apparatus which will permit the consistent and efficient attainment of a desired or controlled degree of pressure reduction within the containers being sealed through the controlled direction of a body of steam or other gas or vapor directly into the container.

Another object of my invention is to provide a method and apparatus by which the steam will be directed into the open mouth of the container in a limited area diametrically of the open mouth of the container, and air and steam will be moved laterally out of the container until substantially complete scavenging has been effected.

A still further object of my invention is to provide a method and apparatus for directing a laminar ribbon of steam into the open mouth of the container and for creating a zone of reduced pressure laterally of the ribbon to aid in the scavenging of contaminated air from within the container.

A still further object of my invention is to provide a method and apparatus in which a downwardly directed ribbon of steam will be provided for passage into the open mouth of the container, and an atmosphere of steam will be provided, rising into the open head of a container closure, said closure passing through the atmosphere of steam in its travel to sealing position on the container.

In order that my invention may be readily understood, I shall describe certain preferred embodiments thereof in which:

50 Figure 1 is a side elevation of a closure-sealing machine embodying my invention;

Figure 2 is a perspective view of a steam distribution head for use in the practice of my preferred method and forming part of my improved apparatus;

Figure 3 is a side elevation of the steam distributor of Figure 2 showing the relative position assumed by the distributor with respect to containers to be sealed;

Figure 4 is a side elevational view showing the position assumed by the closures with a portion of the steam distributor and a plurality of containers passing through the machine;

Figure 5 is a perspective view of a modified steam distributor; and

Figure 6 is a diagrammatic view illustrating a modification of my invention in which a pair of eductors is employed for pressure reduction which aids in the scavenging of air and air admixed with steam from within the container.

Referring to Figure 1, the machine is of more or less conventional type, including a table 2 along which containers are progressively conveyed by means of a chain belt not shown. Edge guides 3 are provided on opposite sides of the table and serve to position the containers in their course of travel through the machine. A cap track 4 is provided which receives a plurality of closures in an inclined position for disposition upon the respective containers as they move through the machine. A closure-applying arrangement 5 in the nature of a spring-actuated chain conveyor is provided, the same being disposed adjacent the closure track 4. The foregoing equipment is of conventional type commonly employed in the steam chamber type of sealing equipment.

In place of a steam chamber, however, there is provided a steam distributor 6 which is shown in Figure 2. The distributor 6 is provided with a dephlegmator chamber 7 adjacent its inlet end which is effective for removing in the conventional manner entrained water from the steam which is inletted through an opening 8 in the distributor. If steam of high quality, substantially free of condensation, is supplied, the dephlegmator may be eliminated. The distributor proper is made up of sheet metal and includes a plenum chamber formed of side walls 9 and 10, top wall 11, and bottom wall 12. The bottom wall is provided with an opening 13 which extends longitudinally thereof, and when the distributor is in position, as shown in Figure 1, the opening 13 will lie generally parallel to the length of the table 2 so that containers 14 moving over the table 2 between the guides 3 will pass under the distributor 6 in alignment therewith. The opening 13 may be of substantially uniform width throughout a major portion of the length of the opening or may be tapered, as shown in Figure 5. The opening 13 preferably flares at the exit end 15 of the distributor, as shown in both Figures 2 and 5. Downwardly directed guards or fins 16 are provided and define the opening 13.

The end wall 17 of the distributor is inclined, as shown in Figure 3, and is provided with an opening 18, as shown in Figures 2 and 5. Mounting brackets 19 are provided for attaching the steam distributor to the machine.

In carrying out the method of my invention, steam at a pressure of a few pounds and a temperature of about 212° F. is inletted into the distributor through the inlet 8. The steam passes through the dephlegmator chamber 7 where it is expanded to slightly above atmospheric pressure, and any condensate in the steam is removed therefrom. The steam of high quality then passes into the plenum chamber and flows therefrom as a downwardly directed laminar

ribbon. The issuing ribbon of steam flows downwardly a short distance, sufficient to penetrate within the container to the upper surface of the container contents. The ribbon is substantially free of turbulence as it issues from the distributor, being of extremely low pressure and being guided by the fins 16; such flow is technically termed a laminar flow, or viscous or streamlined flow to contrast it with a jet flow wherein great turbulence occurs. Referring to Figure 3, containers 14 are filled with food or other products to the line 20 or thereabouts with a head space 21 provided thereabove. The downwardly directed ribbon of steam is confined against lateral movement by the guards or fins 16 so that the ribbon of steam is directed downwardly into the containers, as best illustrated in Figure 6. It will be observed that the width of the opening 13 is less than the width of the open mouth of the container 14 so that the ribbon of steam is directed into the central portion 22 of the container, and the portions 23 and 24 thereof are free for the unrestricted lateral flow of air and steam from within the container. As previously mentioned, the opening 13 is preferably of a width which is less than the width of the container mouth throughout substantially all of the length of the opening. As the container moves progressively under the steam distributor, the ribbon of steam flows into the open mouth of the container into the head space 21; the steam moves downwardly against the surface of the container contents, flowing laterally thereover and passing upwardly and outwardly in the areas 23 and 24, sweeping with it the air within the head space of the container. As the forward progress of the container continues, contaminated air and steam will continue to flow laterally from the areas 23 and 24 of the container; when by the time the container reaches the end of the steam distributor, substantially all or at least a substantial portion of the air will have been removed and replaced with high quality steam.

As shown in Figure 4, the container 14 will then move into a position where a closure 25 will be applied by a mechanism generally indicated by the numeral 26. Such apparatus forms no part of the present invention, the same being illustrated, described, and claimed in the copending applications of Paul Gschwend and the present inventor, Serial No. 757,530, filed June 27, 1947, entitled "Closure-Feeding Devices," now Patent No. 2,481,508, and Harold H. Borthwick, Serial No. 757,477, filed June 27, 1947, entitled "Closure-Release Mechanism," now Patent No. 2,481,495.

The steam passing through the distributor forms an upwardly directed atmosphere through the opening 18 shown in Figure 2. This atmosphere fills the open head of the container closure, and since the fins 16 diverge and form a funnel-like path for steam distribution, an atmosphere of steam is disposed above substantially the entire open mouth of the container and fills the area between the container and its closure. As the container 14 moves forward, a closure 25 is extracted from the track and is positioned upon the container 14, passing through the atmosphere of steam and entrapping steam within the container. The steam atmosphere also prevents the entrance of contaminating air into the container as the closure moves from the track onto the container. After closure

application, the introduced steam is permitted to condense within the container.

In a modification of my invention shown in Figure 5, the opening 13 in the bottom wall 12 of the distributor instead of being substantially uniform in width throughout its length is tapered gradually from the inlet end 27 thereof to the exit end 28 thereof. I have found that this tends to provide a ribbon of steam when supplied at low pressure which has a forward motion along the direction of the length of the opening 13. While this forward motion may not be as rapid as the rate of movement of the containers under the steam distributor, it has been found that this forward motion aids in the sweeping out of air from within the container. In this embodiment, as in the other embodiments shown, the opening 13 is defined by the fins which serve to confine the lateral movement of the steam. The width of the opening 13 is also preferably less than the width of the open mouth of the container to be sealed throughout substantially the full length of the opening 13 so as to permit unrestricted lateral flow of air and air and steam during the movement of the container under the distributor and thus obtain effective scavenging of air from within the head space of the container.

In Figure 6, I have shown a modification of my invention in which eductors 29 and 30 are provided on opposite sides of the steam distributor 6. These eductors serve to create zones of reduced pressure laterally of the opening 13 and aid in the withdrawal of air and air and steam from within the container. This reduced pressure may be attained by means of water injection nozzles 31 and 32 positioned within the eductors for rapidly condensing steam passing into the eductors. Drain lines 33 and 34 are provided in the eductors. Also shown in Figure 6 are extensions 35 on the fins 16 which project into the plenum chamber. These extensions serve to prevent any condensate formed in the plenum chamber from dripping along the fins 16 and into the containers moving thereunder. The condensate flows into the dephlegmator chamber 7 from whence it is discharged through outlet 36.

While I have mentioned low pressure steam slightly above atmospheric pressure, it will be understood that the pressure will vary, depending upon the size of the container, the speed of operation of the machine, the depth of the head space, and other variable factors. It should be maintained as a relatively slowly moving downwardly directed confined ribbon, advancing in laminar flow, so as to avoid the entrainment of excessive quantities of air into the container. While it is preferred to have the ribbon of a width less than the width of the container mouth throughout a major portion, at least, of the length of the ribbon in order to permit lateral scavenging of contaminated air from within the container, the ribbon may be of greater width, particularly where the opening tapers in width so as to create the forward motion of the steam heretofore referred to, this action being effective for scavenging the contaminated air in a direction along the length of the ribbon. Best results are achieved, however, where the ribbon is of less width than the container mouth for a sufficient portion of its length to permit lateral scavenging to remove substantially all of the contaminated air.

The preferred treating medium is steam main-

tained at a temperature of about 212° F., since steam is generally available in large quantities and at low cost in modern food packaging plants. Other heated gases or vapors or mixtures may be employed, however; and if desired, the steam or other vapor may be heated above 212° F. It is well known that the degree of pressure reduction attainable when the head space of a container is filled with steam or the like depends upon the quality of the steam and to a lesser extent also upon the temperature of the steam. I prefer to employ a hot condensable vapor or a mixture in which such vapor is present in a substantial amount. Inert gases of combustion may be employed in some instances, particularly where a high degree of pressure reduction is either unessential or undesirable. Such gases usually contain in excess of 10% of condensable vapor. By superheating steam above 212° F., improved results may be achieved, where a high degree of pressure reduction is particularly desired.

Condensation of the steam in the container may be hastened by the application of jets of cooling water to the container after sealing. This is particularly desirable where the contents are packed hot.

While I have shown in Figure 4 a side-seal press-on type of closure, the method and apparatus of this invention are not limited to the use of this type of closure. Other types may be employed with equally good results.

While I have illustrated and described certain preferred embodiments of my invention, it may be understood that the same may be otherwise embodied and practiced within the scope of the following claims.

I claim:

1. In a method of vacuumizing containers, the steps comprising directing a single ribbon of low velocity steam advancing in flow approaching ideal laminar flow downwardly into the open mouth of a container moving along the length of said ribbon, said ribbon being directed into the container along a narrow path passing through the center of the container mouth, confining the lateral movement of said single ribbon of steam as it enters the container mouth but permitting unrestricted lateral flow within the container and outwardly from the ribbon on either side thereof until substantially all of the air has been scavenged from within the container, and thereafter sealing the container, entrapping steam therein.

2. In a method of vacuumizing containers, the steps comprising establishing a downwardly directed ribbon of low velocity steam advancing in flow approaching ideal laminar flow, progressively moving a container to be vacuum-sealed along the length of said ribbon with the steam displacing a substantial quantity of the air within the container during its progressive movement along the length of said ribbon, simultaneously creating a zone of reduced pressure laterally of the ribbon of steam to withdraw scavenged air laden steam displaced by steam within the container, and applying a closure to the container, entrapping steam therein.

3. In a method of vacuumizing containers, the steps comprising directing a ribbon of low velocity steam advancing in flow approaching ideal laminar flow downwardly into the open mouth of a container moving along the length of said ribbon, confining the lateral movement of the steam as it enters the mouth of the container to a portion only of the opening in the container and simultaneously withdrawing air and con-

taminated steam from within the container until a substantial portion of the air has been removed from the container, establishing an atmosphere of steam contiguous with one end of said ribbon, and moving a closure through said atmosphere and onto the open mouth of a container leaving said ribbon, entrapping steam within the open head of the closure during sealing of the container.

4. In a method of sealing containers under vacuum, the steps comprising establishing a ribbon of low velocity steam advancing in flow approaching ideal laminar flow and moving downwardly and having a forward component of movement in a direction along the length of said ribbon, progressively moving a container to be sealed along the length of said ribbon in the direction of longitudinal flow of steam whereby the steam and container advance together until the steam has displaced a substantial quantity of the air within the container, and applying a closure to the container, entrapping steam therein.

5. In a vacuum-closing machine, a steam distributor comprising a steam chamber having a slot in the bottom thereof for directing a laminar flowing ribbon of steam into the open mouth of a container moving therebelow, and eductors comprising means for creating zones of reduced pressure positioned on opposite sides of said slot for withdrawing air and steam from the container mouth laterally of the zone of steam ejection into the container to effect a scavenging of air within the container and its replacement by steam by the combined action of the evolvent ribbon of steam and the eductors.

6. In a vacuum-closing machine, a steam distributor comprising a steam chamber having a slot in the bottom thereof for directing a laminar flowing ribbon of steam into the open mouth of a container moving therebelow, downwardly directed fins defining the opening in said chamber, and eductors positioned laterally of said fins and comprising means for creating zones of reduced pressure laterally of the zone of steam evolvement.

7. In a vacuum-closing machine in which hot condensable vapor is directed into the open mouth of a container, a vapor distributor comprising a plenum chamber having a substantially unrestricted, longitudinally directed narrow slot extending throughout a substantial portion of the length of the bottom wall of the plenum chamber and of a width throughout a major portion at least of its length which is less than the width of the mouth of a container to be vacuum-sealed for directing a ribbon of vapor advancing in flow approaching ideal laminar flow into the open mouth of a container moving therebelow with an area laterally disposed with respect to the zone of steam ejection into the container for the withdrawal of air and contaminated steam from the container mouth, and means for conveying said container progressively below said opening and substantially parallel to the length of the said opening.

8. In a vacuum-closing machine in which hot condensable vapor is directed into the open mouth of a container, a vapor distributor comprising a plenum chamber having a substantially unrestricted, longitudinally directed narrow slot extending throughout a substantial portion of the length of the bottom wall of the plenum chamber and of a width throughout a major portion at least of its length which is less than the width of the mouth of a container to be vacuum-sealed,

and downwardly directed guards projecting below the bottom wall of said chamber adjacent both sides of the slot for directing a ribbon of vapor advancing in flow approaching ideal laminar flow into the mouth of a container moving therebelow with areas of the container mouth disposed laterally of said guards for the withdrawal of air and contaminated steam from the container mouth.

9. In a vacuum-closing machine in which hot condensable vapor is directed into the open mouth of a container, a vapor distributor comprising a plenum chamber and a vapor inlet into said plenum chamber adjacent the entrance end of said distributor, said chamber having a substantially unrestricted, longitudinally directed slot extending throughout a substantial portion of the length of the bottom of the distributor and increasing in width from the entrance end to the exit end of the distributor for the delivery of vapor advancing in flow approaching ideal laminar flow as a ribbon into the mouth of a container moving therebelow and advancing in similar flow in a direction from the entrance end toward the exit end of the distributor, whereby said ribbon of vapor will move with the container as it travels through the machine.

10. In a vacuum-closing machine in which hot condensable vapor is directed into the open mouth of a container, a vapor distributor comprising a plenum chamber having a substantially unrestricted, longitudinally directed narrow slot extending throughout a substantial portion of the length of the bottom wall of the plenum chamber and of a width throughout a major portion at least of its length which is less than the width of the mouth of a container to be vacuum-sealed for directing a ribbon of vapor advancing in flow approaching ideal laminar flow into the open mouth of a container moving therebelow with an area laterally disposed with respect to the zone of steam ejection into the container for the withdrawal of air and contaminated steam from the container mouth, an inclined end wall in said plenum chamber having an opening therein extending from said slot for establishing a rising atmosphere of vapor from said plenum chamber above said opening, and a closure track disposed in an inclined position above said end wall with the lower end thereof which receives a closure for application to a container disposed in the path of said atmosphere of steam.

11. In a vacuum-closing machine in which hot condensable vapor is directed into the open mouth of a container, a vapor distributor comprising a plenum chamber, a vapor inlet adjacent the entrance end of said plenum chamber, said chamber being of reducing cross-sectional area from its entrance end along its length and having a longitudinally directed narrow slot extending throughout a substantial portion of the length of the bottom of the distributor and increasing in width from the entrance end to the exit end of the plenum chamber, said slot being of a width throughout a major portion at least of its length which is less than the width of the mouth of a container to be vacuum-sealed, and downwardly directed guards projecting below the bottom wall of said chamber adjacent both sides of the slot for directing a ribbon of vapor advancing in flow approaching ideal laminar flow along the length of said slot, whereby said ribbon of vapor will move with the container as it travels through the machine and areas of the container mouth disposed laterally of the guards will permit discharge

of air and contaminated steam from the container mouth.
